MERCHANTISE PACKAGE AND DISPLAY

Frank J. Addis and Paul P. Addis, Brooklyn, N. Y.

Application April 10, 1939, Serial No. 267,201

9 Claims. (Cl. 206—44)

This invention relates to packages or containers used for the packing and shipment, as well as the display of articles of merchandise, and particularly to two similar strips of merchandise, each comprising a series of spaced candle holders with candles arranged therein; and the object of the invention is to provide a package or container comprising an elongated box open at the top for receiving at each longitudinal side portion of the box said article strips with the candles thereof arranged in opposed intermeshing relationship, and equal spacing longitudinally of the box for supporting the candles in horizontal position and also for providing reinforcing means cooperating with the candle holder bodies to retain the complete packed package or container against crushing transversely of the box in the shipment and handling thereof; a further object being to provide a package or container of the character described employing a transparent sheet over the open upper portion of the box to form a closure for said box to protect the candles and candle holders against the collection of dust and dirt thereon, while at the same time supporting said articles against displacement and rendering the same visible in the display of the merchandise; and with these and other objects in view, the invention consists in a package or container constructed as more fully hereinafter described and claimed.

The invention is fully disclosed in the following specification, of which the accompanying drawing forms a part, in which the separate parts of our improvement are designated by suitable reference characters in each of the views, and in which:

Fig. 1 is a plan view of a container showing part of the merchandise in complete form or contour and diagrammatically outlining the remainder of said articles.

Fig. 2 is a section on the line 2—2 of Fig. 1, showing the package in a normal position; and,

Fig. 3 is a view similar to Fig. 2 illustrating the arrangement of the parts when the package is subjected to transverse crushing strains.

In the merchandising of candle holders and candles such as commonly used in the decoration or ornamentation of cakes, or as table ornaments, favors, and the like, it is the general custom and practice to mount and package the candle holders and the candles detached, one with respect to the other. It is the purpose of our invention to provide a unitary merchandise package and display of simple and economical construction wherein a large number of coupled candle holders and candles may be sold in a neat, attractive and

sanitary package at a low retail selling price. At the same time, a package is provided, which in addition to attractively displaying the complete merchandise, also provides a well reinforced package which will compensate for rough handling thereof in shipment or transportation, and prevent breakage or destruction to the several unitary candle holders and candles.

The economical construction of the product herein shown is made possible through the teachings in the method as defined in a companion application filed of equal date herewith on Confection candle holders and the method of constructing the same, from which it will appear that grouped formation of candle holders, as well as grouped assemblage of candles in the holders is made possible, thus simplifying the production of the merchandise supporting strips hereinafter described.

In the accompanying drawing, 5 represents an elongated box having a bottom wall 5a, side walls 5b, end walls 5c, and open at the top throughout the length thereof. Arranged in the box is an article supporting and reinforcing member 6 comprising a top wall 7, depending side walls 8, which normally flare outwardly to a slight extent, and laterally extending flanges 9 arranged upon the bottom wall of the container 5a and extending in the direction of the side walls 5b thereof.

At 10, 10a, are shown two similar merchandise supporting strips, members, or parts, and as these parts are of identical construction, the brief description of one will apply to the other. It will be understood that one strip 10 is arranged longitudinally of the inner surface of one side wall 5b, and the other strip 10a is arranged longitudinally of the inner surface of the other side wall. Both of these strips are of a width equal to the height of the walls 5b with respect to the upper surface of the bottom wall 5a so that the upper edges of

the strips 10, 10a will lie flush with the upper edges of the side walls as will appear in Fig. 2 of the drawing. Thus when a transparent "Cellophane," or other strip 11 is arranged over the upper open end of the box, and down along the sides and bottom of the box and secured together as at 11a, a transparent closure will be provided which will hold the strips 10, 10a against displacement from the container. In this connection, it will be understood that other means may also be provided for this purpose, for example by applying a little glue or other adhesive between the strips 10, 10a, and the sides 5b of the container at longitudinally spaced intervals.

Arranged upon and secured to the surface of 55

the strip 10, 10a are a series of longitudinally arranged and equally spaced candle holder bodies 12 composed of edible sugar confection, each body comprising a base portion 13, preferably of 5 one colored confection, and a portion 14 of another colored confection; the latter having an aperture 15 therein snugly receiving one end of the candle 16 to be supported in the holder.

The transverse dimensions of the container 5 10 are such as to freely receive the candles when arranged in the holders of each strip so that the tip ends 16a of the candles will be arranged in spaced relation to the adjacent side wall 5b of the container; whereas conical projections 14a, 15 on the part 14 of the holder 12 will be spaced slightly from the ends of the top wall 7 of the supporting and reinforcing member 6 as noted in Fig. 2 of the drawing. It will thus be seen that when the container is subjected to a transverse 20 crushing strain, as noted in Fig. 3, the conical projections 14a of the body 14 will engage the side walls 8 to move the same into perpendicular position, thus applying the strain directly upon the transverse top wall 7, and relieving the strain 25 upon the candle 16. While the side walls 5b may actually engage the tip ends 16a of the candles and depress the same slightly, the strain directly upon the candle is relieved through the reinforcing wall 7. In the normal position of the 30 assemblage as seen in Fig. 2, the walls 8 will retain the parts against shifting, especially if the strips 10, 10a are not directly secured to the side walls 5b.

It will also be apparent that the candles 16 35 of one strip 10 are intermeshed or arranged alternately with those of the other strip 10a, and the tip ends 16a of the candles are disposed between the candle holders 12 of the opposed strip as clearly seen in Fig. 1. This maintains an even 40 and balanced alignment of the candles and holders longitudinally of the container. One end of each of the strips 10, 10a will be supported in engagement with one end wall 5c of the container. To avoid difficulty in assemblage of the separate strips in the containers, both ends are 45 maintained at the same length, but if desired, these strips may be formed longer at one end and simply reversed in their mounting in the container. However, we have not found this to 50 be necessary and therefore the more simple showing is illustrated.

However, as above stated, if one or more small 55 applications of adhesive are applied to the strips 10, 10a, they may be retained against longitudinal shifting as well as vertical shifting with respect to the side walls 15b. It is preferred that a limited amount of adhesive be used so as to facilitate removal of the strips from the container when it is desired to use the candles. By severing the separate candle holders one from the other, they may be used independently and the cardboard or other strips 10, 10a, may be of such material as to form base supports for the candle holders when used as ornaments or table decorations. On the other hand, when used as 65 cake decorations, the strips 10, 10a are moistened, which will free the sugar confection candle holders 12 from the strip to facilitate placement on a cake. At this point, it is well to call 70 attention to the fact that when the candles have been burned sufficiently, the same may be removed from the holders and the remaining candle holders may be consumed with the cake by reason of utilizing the edible sugar confection 75 in the construction thereof.

In other words, no metal, paper, wood, or other candle holding elements are arranged within or form part of the holders 12, as is quite common in the usual construction of candle holders of this type.

It will of course be apparent that merchandise packages and displays of the character under consideration can be made up of various numbers of candle holders and candles, and this is especially true in the construction of similar 10 packages having a lesser number of candle holders and candles than those shown in Fig. 1. It will also be apparent that the relative sizes of the candles and candle holders may be varied to adapt the package to different grades and 15 styles of merchandise of the type and kind under consideration.

In using contrasting colors in the base 12 and body 14 of the holders, very attractive appearances will be provided on the resulting devices, 20 and the candles used may be of a color in harmony with one of the colors employed in the bodies 13, 14, or may be of a color contrasting thereto. An example of the last illustration would be to employ red candles mounted in a 25 white body 14, the latter arranged upon a blue base 13. However, in more conventional uses, the pink, white, green, and yellow shades are more commonly used for cake decoration purposes. Combinations of the various holiday or 30 memorial seasons may also be used. This is especially true in the production of table favors and decorations. At this time it will be apparent that the contour of the candle holder bodies 35 12 may be varied to produce different ornamental effects, and of course, the dimensions and contour of the container as well as the supporting and reinforcing member 6 will be modified to suit differences in the structure of the candle holders.

The supporting and reinforcing member 6 may also be properly described as a spacing member which forms at the longitudinal side portions of the container, longitudinal channels for the reception of part of the merchandise, namely, the 45 candle holders 12; whereas the upper wall 7 forms a longitudinal table or platform upon which the candles rest in a horizontal position.

Having fully described our invention what we claim as new and desire to secure by Letters 50 Patent, is:

1. In combination with elongated merchandise strips having candles and candle holders secured to and supported upon one surface of the strips at equal longitudinally spaced intervals, of a 55 packing and display container for a pair of said strips comprising an elongated receptacle having a bottom, side and end walls, with the top of said receptacle open, said strips being arranged upon inner surfaces of the side walls of the receptacle 60 within the vertical boundaries thereof with the candle holders and candles protruding from the inner surfaces of said strips into the receptacle in a horizontal position transversing said receptacle, the candles of one strip being disposed 65 intermediate the candles of the other strip, and means within the receptacle supporting the candles in horizontal position and retaining the candle holders against appreciable transverse movement in said receptacle.

2. In combination with elongated merchandise strips having candles and candle holders secured to and supported upon one surface of the strips at equal longitudinally spaced intervals, of a 70 packing and display container for a pair of said 75 strips comprising an elongated receptacle having a bottom, side and end walls, with the top of said receptacle open, said strips being arranged upon inner surfaces of the side walls of the receptacle within the vertical boundaries thereof with the candle holders and candles protruding from the inner surfaces of said strips into the receptacle in a horizontal position transversing said receptacle, the candles of one strip being disposed intermediate the candles of the other strip, and means within the receptacle supporting the candles in horizontal position and retaining the candle holders against appreciable transverse movement in said receptacle.

- strips comprising an elongated receptacle having a bottom, side and end walls, with the top of said receptacle open, said strips being arranged upon inner surfaces of the side walls of the receptacle 5 within the vertical boundaries thereof with the candle holders and candles protruding from the inner surfaces of said strips into the receptacle in a horizontal position transversing said receptacle, the candles of one strip being disposed intermediate the candles of the other strip, means 10 within the receptacle supporting the candles in horizontal position and retaining the candle holders against appreciable transverse movement in said receptacle, said last named means comprising a longitudinally arranged bridging and reinforcing member reinforcing the receptacle against transverse crushing strain. 15
3. In combination with elongated merchandise strips having candles and candle holders secured to and supported upon one surface of the strips at equal longitudinally spaced intervals, of a packing and display container for a pair of said strips comprising an elongated receptacle having a bottom, side and end walls, with the top of said receptacle open, said strips being arranged upon inner surfaces of the side walls of the receptacle within the vertical boundaries thereof with the candle holders and candles protruding from the inner surfaces of said strips into the receptacle 20 in a horizontal position transversing said receptacle, the candles of one strip being disposed intermediate the candles of the other strip, means within the receptacle supporting the candles in horizontal position and retaining the candle 25 holders against appreciable transverse movement in said receptacle, said last named means comprising a longitudinally arranged bridging and reinforcing member reinforcing the receptacle against transverse crushing strain, and a trans- 30 parent sleeve enveloping the receptacle and forming a closure for the open top of the receptacle. 35
4. A candle and candle holder shipping and display package of the class described, comprising an elongated narrow open container having bottom, side and end walls, a thin merchandise supporting strip arranged longitudinally and flatly upon the inner surface of each opposed side wall of the container, a plurality of candle holders secured to the inner exposed surfaces of 40 the strips at longitudinally spaced intervals, the holders on one strip being in staggered relationship to the holders of the opposed strip, candles supported in the holders and protruding from the inner opposed surfaces thereof to extend transversely of said container with the free tip ends of the candles supported on the holders of one strip arranged intermediate the candle holders of an opposed strip, means supported upon and extending above the bottom wall of the container for supporting each of the candles in horizontal position throughout substantially the length thereof which is disposed between opposed holders and with the candles in alinement with the supports in said holders, said last named means comprising a yoke-shaped reinforcement extending the full length of the container having a wide top wall upon which the candles rest, and depending side walls having laterally extending flange portions, and the side walls of said reinforcement being arranged in close proximity to inner opposed surfaces of the candle holders to support said holders and candles against movement transversely of the container, and means for holding said strips including the candles and candle holders thereon against displacement through the open top of the container. 45
5. A candle and candle holder shipping and display package of the class described, comprising an elongated narrow open container having bottom, side and end walls, a thin merchandise supporting strip arranged longitudinally and flatly upon the inner surface of each opposed side wall of the container, a plurality of candle holders secured to the inner exposed surfaces of the strips at longitudinally spaced intervals, the holders on one strip being in staggered relationship to the 50 holders of the opposed strip, candles supported in the holders and protruding from the inner opposed surfaces thereof to extend transversely of said container with the free tip ends of the candles supported on the holders of one strip arranged intermediate the candle holders of an opposed strip, means supported upon and extending above the bottom wall of the container for supporting each of the candles in horizontal position throughout substantially the length thereof which is disposed between opposed holders and with the candles in alinement with the supports in said holders, said last named means comprising a yoke-shaped reinforcement extending the full length of the container having a wide top wall upon which the candles rest, and depending side walls having laterally extending flange portions, and the side walls of said reinforcement being arranged in close proximity to inner opposed surfaces of the candle holders to support said holders and candles against movement transversely of the container, and means for holding said strips including the candles and candle holders thereon against displacement through the open top of the container. 55
6. A candle and candle holder shipping and display package of the class described, comprising an elongated narrow open container having bottom, side and end walls, a thin merchandise supporting strip arranged longitudinally and flatly upon the inner surface of each opposed side wall of the container, a plurality of candle holders secured to the inner exposed surfaces of the strips at longitudinally spaced intervals, the holders on one strip being in staggered relationship to the 60 holders of the opposed strip, candles supported in the holders and protruding from the inner opposed surfaces thereof to extend transversely of said container with the free tip ends of the candles supported on the holders of one strip arranged intermediate the candle holders of an opposed strip, means supported upon and extending above the bottom wall of the container for supporting each of the candles in horizontal position throughout substantially the length thereof which is disposed between opposed holders and with the candles in alinement with the supports in said holders, said last named means comprising a yoke-shaped reinforcement extending the full length of the container having a wide top wall upon which the candles rest, and depending side walls having laterally extending flange portions, and the side walls of said reinforcement being arranged in close proximity to inner opposed surfaces of the candle holders to support said holders and candles against movement transversely of the container, and means for holding said strips including the candles and candle holders thereon against displacement through the open top of the container. 65
7. A shipping and display container of the class described comprising an elongated box having bottom, side and end walls, and being open at the top, means arranged longitudinally of the box and upon the upper surface of the bottom wall thereof forming within the box and in conjunction with said side walls two elongated narrow channels longitudinally of the side walls and an intermediate raised table portion extending throughout the length of the box and arranged inwardly of the upper end of the box, each of said channels being adapted to receive a plurality of articles of merchandise spaced longitudinally thereof, the articles including stem portions transversing the box and supported upon said table portion. 70
8. A shipping and display container of the class described comprising an elongated box having bottom, side and end walls, and being open 75

at the top, means arranged longitudinally of the box and upon the upper surface of the bottom wall thereof forming within the box and in conjunction with said side walls two elongated narrow channels longitudinally of the side walls and an intermediate raised table portion extending throughout the length of the box and arranged inwardly of the upper end of the box, each of said channels being adapted to receive a plurality of articles of merchandise spaced longitudinally thereof, the articles including stem portions transversing the box and supported upon said table portion, and said means comprising an elongated strip yoke-shaped in cross sectional form and having side flange portions resting upon the bottom wall of the box.

9. A shipping and display container of the class described comprising an elongated box having bottom, side and end walls, and being open at the top, means arranged longitudinally of the box and upon the upper surface of the bottom

wall thereof forming within the box and in conjunction with said side walls two elongated narrow channels longitudinally of the side walls and an intermediate raised table portion extending throughout the length of the box and arranged inwardly of the upper end of the box, each of said channels being adapted to receive a plurality of articles of merchandise spaced longitudinally thereof, the articles including stem portions transversing the box and supported upon said table portion, said means comprising an elongated strip yoke-shaped in cross sectional form and having side flange portions resting upon the bottom wall of the box, and elongated strips arranged upon inner surfaces of the side walls of the box forming means for supporting and spacing the articles of merchandise longitudinally of said channels. 5 10 15
